JOHN M. TRACY AND FRANCIS R. SCHERER, OF ROCHESTER, NEW YORK, ASSIGNEES TO
PROSE-MACO MANUFACTURING COMPANY, OF KANSAS CITY, MISSOURI, A COR-
PORATION OF MISSOURI

LOCKING DEVICE FOR BLACKBOARDS

Application filed June 29, 1929. Serial No. 374,778.

The present invention relates to locking devices for movable exhibitors and consists in the combinations and arrangements of elements hereinafter described and particularly set forth in the accompanying claims.

The invention has for its purpose to provide a locking device for hinged frame structures, but more particularly for swinging blackboards, to the end that the same may be securely held in their closed or concealed position and therefore the matter written or otherwise exhibited thereon may not be left liable to unauthorized inspection, erasure, or for other interference.

15 The invention is designed as an improvement for use in connection with our U. S. patent on "Blackboard", described in Patent No. 1,596,457, dated August 17, 1926, and from an inspection of which the applica-
20 bility of the present invention will be apparent.

The invention is shown by way of illustration in the accompanying drawings, wherein:

25 Figure 1 is a perspective view showing the locking device in applied position.

Figure 2 a detailed view showing the locking device in released position.

Figure 3 a detailed view showing the lock-
30 ing device, per se.

Figure 4 a side elevational view thereof, and;

Figures 5 and 6 illustrate a modified construction.

35 Referring to the construction in further detail the invention consists of a hollow post 5 suitably secured to a base plate 6 adapted to be fastened to the wall or other structure on which the several blackboard frames or

40 panels A are hingedly mounted and immediately adjacent thereto as shown in Figure 1.

A stud 7 is screw threaded in the hollow post portion 5 and has its adjusted position secured therein by the set screw 8 as shown in Figures 3 and 4. The outer end of stud 7 is reduced as at 9 to receive the bifurcated end 10 of the swinging arm 11 which is constructed preferably of flat-like metal as shown.

The free end 12 of said arm 11 has a rectangular shaped aperture 13 adapted to receive the boss 14 that forms an integral part of the bracket 15 that is secured to the lower and outer corner of the frame B of the black-
55 board A as indicated in Figure 1. Said corner bracket 15 may be located on either the upper or lower corner of the frame and the boss 14 thereof may project from the side of said bracket if preferred.

When the several frames or blackboards are swung to one side as shown in Figure 1 the swinging arm 11 is brought to engage the boss 14 and in this position the hasp 16 of the padlock 17 is passed through 60 the aperture of the boss and thus the several leaves or frames of the blackboard are secured free from disturbance for reasons heretofore stated.

Referring to Figures 5 and 6 the device 70 consists of a similar hollow post 5, having a stud or arm 7 screw-threaded thereon as in the former construction, and the free end of said post or arm 7 is apertured as at 18 to engage the boss of the innermost 75 frame or blackboard section. A plurality of hinged link members 19 have hinged support 20 with the rigid arm 7 and the opening in each link is adapted to receive the boss 14 of the bracket frame 15 as above de-
80 scribed.

It will therefore be seen that with this modified construction the locking device is adapted to engage and secure one, two, three or four of the blackboards, as desired, and 85 thus leave the remainder free. In all other respects the construction of device and its manner of operation are identical with that above described.

It will be understood by those skilled in 90 the art that changes may be made in our device without departing from the spirit of the invention and therefore we do not limit ourselves to the precise construction shown in the drawings and described in the speci- 95 fication but only as indicated in the appended claims.

What is claimed as new is:

1. The combination with a plurality of swinging exhibitors, of locking means there- 100

for comprising a fixedly mounted socket piece, an arm rigidly mounted in the socket piece, and a plurality of links on said arm adapted to engage with said exhibitors, for the purpose set forth.

2. A device of the character described comprising a socket piece adapted to be fixedly mounted on a support, a rigid arm screw-threaded into said socket piece, and a plurality of link members mounted on said rigid arm for the purpose set forth.

3. The combination with a plurality of hingedly mounted frames or panels, and a support; of a locking device for said frames comprising a socket piece mounted on the support, a hasp mounted on the socket piece, and a lug on the outermost frame adapted to engage said hasp and hold all of the frames against swinging movement, substantially as set forth.

In witness whereof, we have hereunto set our hands at Rochester, N. Y., this 14th day of June, A. D. nineteen hundred and twenty-nine.

25

JOHN M. TRACY.
FRANCIS R. SCHERER.
